UNITED STATES PATENT OFFICE.

HARRY C. SILLETT AND ALBERT W. COWAN, OF KANSAS CITY, MISSOURI, ASSIGNORS OF ONE-THIRD TO WILLIAM M. MYERS, OF ST. JOSEPH, MISSOURI.

HYDROCARBON-GAS GENERATOR AND BURNER.

1,346,770.

Specification of Letters Patent. Patented July 13, 1920.

Application filed July 24, 1918. Serial No. 246,615.

To all whom it may concern:

Be it known that we, HARRY C. SILLETT and ALBERT W. COWAN, citizens of the United States, both residing at Kansas City, 5 in the county of Jackson and State of Missouri, have invented new and useful Improvements in Hydrocarbon-Gas Generators and Burners, of which the following is a specification.

This invention relates to hydro-carbon gas generators and burners and it consists in the novel features hereinafter described and claimed.

An object of the invention is to provide 15 a burner of simple and durable structure having means for effectually converting hydro-carbon oil into gas which is consumed at the burner proper and the heat from the flame of the burning gas is utilized as means 20 for transforming the oil from a liquid to a gaseous state.

In the accompanying drawing:—

Figure 1 is a side elevation of the burner with parts broken away.

Fig. 2 is a transverse sectional view of the burner.

Figs. 3 and 4 are detail views of the features of the invention.

The burner comprises a casing 1 constituting a mixing chamber which is mounted upon suitable legs 2. The top portion of this chamber is provided with a plurality of domes 3 which are spaced from each other by an intervening valley 4. The sides of 35 the chamber 1 and the tops of the domes are provided with transversely disposed slits 5 through which the gas may emit from the chamber. A fender plate 6 is located at one end of the retort and the chamber 40 is provided in its interior and upon its bottom with a baffle wall 7. A curved pipe 8 is connected at one end with one end of the chamber 1 and has its other end terminating adjacent the fender 6.

A pipe 9 is supported above the chamber 1 and extends above the valley 4 between the domes 3. The pipe 9 is provided with a spirally disposed corrugation 10, which extends longitudinally of the said pipe. The 50 object in providing the corrugation 10 is to increase the surface of the pipe 9 which is exposed to the flame from the chamber as hereinafter described. A nipple 11 is screwthreaded in one end of the pipe 9 and 55 passes through the fender 6. The discharge

end of the nipple 11 is opposite the receiving end of the pipe 8 and is slightly spaced therefrom as indicated in Fig. 1 of the drawing. A body 12 is screwthreaded upon the opposite end of the pipe 9 and oil may 60 be let into the body 12 through a nipple 13 located at the side of the said body. A stem 14 traverses the length of the body 12 and the pipe 9 and enters the nipple 11. That end of the stem 14 which is located within 65 the nipple 11 is pointed whereby the said stem may serve as a needle valve. The stem 14 has screwthread engagement with the body 12. The stem 14 is provided at its outer end with a laterally disposed handle 15. A wick 16 is coiled around the intermediate portion of the stem 14 and is housed within the pipe 9. The wick 16 is composed of strands of wire twisted together and the said wick serves as means 70 for retarding the passage of the oil through the pipe 9.

The operation of the burner is as follows:—Assuming that oil is admitted into the pipe 9 through the body 12 and that 80 the stem 14 is at an open position with relation to the nipple 11 the oil passes through the pipe 9. When the pipe 9 is heated the oil is transformed from a liquid condition to a gas and the gas flows through the nipple 11 and mixes with the external air and this mixture passes into the pipe 8 and from the pipe into the chamber 1. The baffle plate 7 directs the mixture upwardly toward the slit 5. The mixture passes through the 85 slit 5 where it is ignited at the outer surface of the chamber 1, and consequently the pipe 9 is enveloped in flame and this supplies the heat to convert the hydro-carbon from a liquid to a gas.

From the foregoing description taken in conjunction with the accompanying drawing it will be seen that a hydro-carbon burner of simple structure is provided and that the same may be economically used for 90 employing a hydro-carbon gas for heating purposes and the flame which supplies the heat is used for converting the hydro-carbon oil from a liquid to a gas.

Having described the invention what is 95 claimed is:—

A device of the character described comprising a casing constituting a chamber, the top of said casing having its side portions formed as domes separated by a longitudi- 110

nal valley, the top of said casing and domes being slit to provide burner openings, a plate at one end of said casing extending thereabove, a curved pipe communicating 5 at its lower end with one end of said casing and having its upper end terminating adjacent said plate, a nozzle carried by said plate in alinement with the upper end of said pipe, a retort pipe supported above 10 said valley and connected and communicat-

ing with said nozzle, a fuel supply pipe leading into said retort pipe, and a stem extending longitudinally through said retort pipe and movable to regulate the opening of said nozzle.

15

In testimony whereof we affix our signatures.

HARRY C. SILLETT.
ALBERT W. COWAN.
